CIGARETTE WITH IGNITER ELEMENT AND METHOD OF MAKING SUCH CIGARETTE

Francesco De Capitani, Milan, Italy

Application March 15, 1954, Serial No. 416,256

Claims priority, application Italy March 18, 1953

7 Claims. (Cl. 131—7)

This invention relates to a process for the addition of end members, and in particular igniting members, or the like, to cigarettes while being manufactured, and to cigarettes thereby manufactured.

A number of processes for making cigarettes or the like provided with suitable end members such as igniting members which can be lighted by striking, and the like, are already known.

However, many inconveniences and drawbacks are encountered when carrying into practice the above mentioned processes. The main drawback depends undoubtedly on the fact that the cigarettes cannot be manufactured in only one high speed step, such as on the modern high production machines, by which more than 1,200 cigarettes per minute can be manufactured.

At present, it seems more convenient to manufacture cigarettes provided with end members by means of two independent machines, i. e. a high output machine, designed for the manufacture of conventional cigarettes, which are then forwarded to a second machine, whereon the required member is added on one cigarette end.

It follows that the remarkable advantages shown by an improved type of cigarette, such as a cigarette provided with holder and igniting member, are cancelled by the high manufacturing costs and by the low output.

The main object of this invention is to provide a process for the high-speed manufacture of cigarettes provided with the aforespecified type of end members such as igniting members or the like at a production rate of the same order as that which can be attained with the present machines for the continuous manufacture of cigarettes.

A further object of the invention consists in the manufacture of cigarettes of the aforespecified type by means of the conventional automatic machines, to which suitable equipment has been added, in order to allow the proper fitting of end members into the cigarettes while they are being conventionally manufactured, by laying the same members properly spaced on the paper strip wherefrom, after it has been wound around the tobacco roll, the cigarettes are cut. All this is accomplished without reducing the operating speed of the machine, and above all prevents damage to the features and characteristics of cigarettes thus manufactured.

The process according to this invention is characterized in that elements, each of which is made-up of two end members, are set, properly spaced, on the paper strip designed to enclose the tobacco roll. Said space must correspond to the length of at least one cigarette, whereupon the cigarettes are cut by making a cut through the middle of said element. Thus each cigarette will be provided with the end members at least in one of their ends.

Such a basic inventive idea can be carried into practice in a number of different ways, depending on the type and features of the end member which is to be fitted to the cigarette.

2

Assuming that the end member to be fitted to the cigarette is an igniting member, then a strengthening section having an igniter incorporated therein is applied first of all to paper strip designed to enclose the tobacco roll. Such a strengthening section is then rolled-up and enclosed within the cigarette paper tube. In some cases a continuous tobacco roll can thereby be enclosed within the paper strip. Then, the strengthening tube enclosed within the paper strip is cut at the middle, whereby each cigarette will be provided with a built-in igniting member.

Suitable sticking means can be used to apply the elements made-up by two opposed end members to the paper strip, whereby the elements are securely kept in their relative positions while the paper strip is being fed into the machine.

Should an igniting member be fitted on the cigarette ends, the process according to the invention consists in providing square strengthening sections, provided on one of their faces with a rib made of a substance which can be ignited by striking. Then holes or slots are cut in the cigarette paper strip and the square strengthening sections are applied thereon in such a manner that they have their ribs directed along the longitudinal axis of the strip, and are to be exposed through said holes or slots, whereupon the tobacco roll is set on the paper strip and said strengthening sections and paper strips are rolled up and sealed around the tobacco, whereby the strengthening sections are rolled up enclosed, together with the tobacco, within the outer paper tube, leaving the lighting rib exposed through the holes or slots. Finally the continuous tube, coming out of machine, is cut at the middle of the strengthening sections, whereby cigarettes provided on one end with an igniting member are obtained.

According to the invention, the section by which the lighting rib is supported, has a strip-like extension having one of its faces partly coated with a compound designed to cause lighting of the rib formed on the strengthening section. Said extension is set in such a manner in relation to the cigarette, so as to have one end in the inside thereof, while the opposite end is projecting out of the cigarette as a tab, which can be seized and torn off, to remove from the cigarette the lighting strip, without damage of the paper tube within which the cigarette is enclosed.

The strengthening sections, as well as the strip-like extensions, could also be cut out from continuous elements, previously provided with a longitudinal lighting rib and a striking surface.

The further objects and advantages of the invention, as well as the features of cigarettes thus obtained, will be better understood by the following description of some preferred forms of said invention, taken with the accompanying drawings, said description and drawings being given only as an example thereof.

In the drawings:

Fig. 1 is a top and bottom plan view of a strip of cigarette paper having a slot therein and having parts placed thereon which will form the igniting element of the cigarette in its finished form;

Fig. 2 shows the parts of Fig. 1 after they have been rolled up around a tobacco roll to form a cigarette and have been cut midway of the igniting element to form two cigarettes with igniting elements at opposed ends thereof;

Fig. 3 is a cross section along line 3—3 of Fig. 2;

Fig. 4 is a schematic view of a method of assembling the cigarettes according to the invention;

Fig. 5 is a plan view of a modified form of striking tab; and

Fig. 6 is a plan view of the striking tab of Fig. 5

as it is incorporated in a tube prior to being cut into individual cigarettes.

It is of course to be understood that the sizes of the parts shown in the drawings have been exaggerated in order to illustrate clearly the inventive concept involved. The actual dimensions are on the order of conventional cigarette paper sizes.

The cigarettes as shown in the Figs. 1 to 3 inclusive is provided on one of its ends with a lighting member.

Referring now to Figs. 2 and 3, the cigarette A consists, as already well known, of a paper tube B, within which the tobacco roll C is enclosed.

The lighting member consists of a short tube section K, the outside diameter of which is substantially the same as the inside diameter of tube B, and which is made of a conveniently treated, cellulose paper material.

A rib G, made of a material like that of which matches are made, i. e. which lights by striking, is formed outside the longitudinal middle section of said tube section K.

At least a part of said rib is exposed at the end of the cigarette, through an open ended slot formed from elongated slot H, cut along the longitudinal axis of paper strip B, in order to allow the upper part of said rib to be struck against a rough surface, when the cigarette is to be lighted.

The process for the manufacture of the aforescribed type of cigarette is as follows:

At first, the strengthening section which eventually forms tube K is prepared by starting from a roll D, as seen in Fig. 4 made up by a strip of previously treated cellulose material whereon one or more ribs G have been applied. Square sections K of such dimensions that their width L (as seen in Fig. 1) is almost equal to the circumference of tube B of cigarette A are cut out of the strip.

The paper strip B, as unrolled from the roll M, has a longitudinal slot H cut along the longitudinal axis of strip B (see Fig. 1), said slot being spaced two cigarette lengths from the next adjacent slot. The strengthening section K with a length L' covers the slot H and extends past the ends thereof. In the case as shown in the figures, the strengthening sections K are cut each time from the strip as it is unrolled from roll D, and are set on strip B in such a manner that the rib G covers the slots H.

The spacing between successive slots is equal to twice the length of a cigarette A, i. e. said spacing corresponds to two cigarettes. The strengthening sections K are applied to paper strip B in such a manner that they correspond exactly with the slots H, previously cut in the said strip. Recourse could be made to a suitable sticking means to keep said strengthening sections securely in their proper positions.

The strip B thus prepared is fed into a cigarette machine in the conventional manner, and the tobacco roll is set thereon, whereupon the whole is forwarded to mechanisms by which the paper strip is rolled-up, closed and sealed along its longitudinal edges, the strengthening sections K thus being formed into tube sections. Thus, a continuous tube is obtained, within which the tobacco roll, and the rolled-up strengthening sections are enclosed. As can be easily appreciated the tobacco roll will also be enclosed, without interruption, within the short tube sections K formed by the rolled-up strengthening sections K.

Thus a continuous tube P is obtained, wherefrom the cigarettes A and A' are cutoff by the cutter Q. The tube P is first cut by the cutter Q on the center of rolled-up strengthening section K, while the subsequent cut is made at a point where no strengthening section exists. It follows that the means by which the strengthening sections K are cut from the strip unrolled from roll D, and then set onto the strip B, must work at half the operating speed of cutter Q. Thus, it is possible to manufacture cigarettes provided with lighting members of the aforescribed type at the same production rate as that for conventional cigarettes.

As seen in the figures, the cigarette may be provided with a striking tab R which projects from the sides of the cigarette to enable it to be withdrawn and the igniter rib G rubbed thereon to ignite the igniter rib.

As seen in Fig. 1, the striking tab R has a roughened surface S thereon, the surface S being of a material which when rib G is rubbed thereon will cause rib G to ignite. This surface is placed face up on the strengthening section K before the assembly is wrapped around the tobacco roll C, so that in the finished cigarette the roughened surface S is against the tobacco roll C. The end of the tab R is allowed to extend over the edge of strip B so that, as seen in Fig. 3, when the assembly is wrapped around tobacco roll C, the tab R projects through a longitudinal aperture R' left along the joint of the edges of strip B.

Fig. 4 shows the rolls M, D and T, wherefrom the paper strip B, the strip K for the strengthening sections, and the strip for the striking latch R—S are respectively unrolled.

The strip R—S is arranged, in respect of strip K, in such a manner as to allow the section R to project over the edge of strip B while the striking surface S lies over said strip K.

The strips K and R—S could be stuck together, thus forming double thickness quadrilateral sections K—R, which would then be applied on the strip B and associated with the slots H.

As shown by Figs. 1 and 2, the longitudinal axis of slots H is parallel to, or coincident with the longitudinal axis of cigarette paper strip B. The strengthening quadrilateral sections K—R are set on said strip B by placing the sections in such a manner that the rib G corresponds to the slot H, while the latch R projects over the edge of the strip B, thus forming the tab to be seized and pulled when the cigarette is to be lighted.

Then, the tobacco roll is set onto the strip B, and the latter strip is rolled-up and sealed, together with the quadrilateral sections K—S, the first of which is rolled-up so as to form a short tube section K, while, as shown by the Fig. 2, the double latch R projects from one side of continuous tube P through a longitudinal aperture R' defined by the edges of the strip B, from which tube the cigarettes A and A' are cut-off.

The cutter Q, by cutting the tube section K together with the strengthening sections R—S in two like halves, causes separation of the cigarette A from subsequent cigarette A', leaving on adjacent ends of both cigarettes the igniting ribs G and the striking zones S located in the inside of paper tube formed by the paper strip B.

The striking surface S is pulled out of the cigarette by means of the tab R, through the aperture R' between the edges of strip B and the rib G is rubbed on the surface S.

To ensure a positive seal of edges of strip B at the end of cigarette A, when the cigarette is provided with the striking tab R, V notches may be cut from the strengthening sections R—S. The square bottom W of said notches has a width sufficient to allow the edges X—X of strip B (see Fig. 6) to overlap along the section corresponding to notch V.

The quadrilateral strengthening sections K and R—S are set on the strip B in such a manner that the bottom W of notch V is inside the strip edge, to allow overlapping of strip edges along the section corresponding to said notch V, while the strip B is being rolled-up. The tabs R thus project from the tube P through longitudinal apertures R' defined between the edges of the strip B.

It follows that both cigarettes A and A', even after their separation from one another, will be positively sealed along the edges of strip B, and also along the latch R.

What I claim is:

1. In a process for the manufacture of cigarettes in which a flat strip of paper of a width slightly greater than the circumference of the cigarettes is wrapped around a roll of tobacco, that improvement comprising the steps of forming an aperture in said strip of paper, positioning

on said strip of paper on the side thereof which will be next to the tobacco roll and over said aperture an element comprising a lighting member of slightly less width than said strip and an igniter rib thereon, said igniter rib lying against said paper strip over said aperture and being longer than said aperture in the longitudinal direction of said strip, and after the strip is wrapped around the roll of tobacco and secured, cutting said wrapped roll transversely to the length thereof through said aperture.

2. The improvement as claimed in claim 1 in which said aperture is elongated in the direction of the length of said strip.

3. The improvement as claimed in claim 1 in which the positioning of said element comprises adhering said element to said strip.

4. In a process for the manufacture of cigarettes in which a flat strip of paper of a width slightly greater than the circumference of the cigarettes is wrapped around a roll of tobacco, that improvement comprising the steps of forming in said strip of paper an aperture elongated in the direction of the length of said strip of paper, cutting from a continuous band of lighting member with a longitudinal igniter rib thereon a length longer than said elongated aperture, positioning said length on said strip of paper on the side thereof which will be next to the tobacco roll and over said aperture with said igniter rib lying against said paper strip over said aperture and extending in the longitudinal direction of said strip, and after the strip is wrapped around the roll of tobacco and secured, cutting said wrapped roll transversely to the length thereof through the center of said aperture.

5. In a cigarette having a roll of tobacco wrapped in paper, a lighting member in the form of a tube positioned within the paper at one end of the cigarette, a longitudinal igniter rib on said tube, said paper having a slot 35 therein in the portion covering said tube, said igniter rib being exposed through said slot, said tube and paper hav-

ing a longitudinal aperture therein, and a striking tab positioned within the tube between the roll of tobacco and the tube with the striking portion toward said roll of tobacco, said tab projecting laterally from the cigarette

5 through said longitudinal aperture.

6. In a cigarette having a roll of tobacco, a paper wrapping wrapped around said roll, a lighting member in the form of a tube positioned within the paper wrapping at one end of said cigarette, and a longitudinal igniter rib on said tube, the end of said paper wrapping within which said tube is positioned having an open ended slot therein, one end of said igniter rib being exposed through said slot.

7. In a cigarette having a roll of tobacco, a paper wrapping wrapped around said roll, a lighting member in the form of a tube positioned within the paper wrapping at one end of said cigarette, and a longitudinal igniter rib extending the full length of said tube on the outside thereof, the end of said wrapping paper within which said tube is positioned having an open ended slot therein of a length shorter than the length of said tube, and a portion of said rib being exposed radially outwardly through said slot.
